UNITED STATES PATENT OFFICE.

**MARK N. RUSSELL, OF SYRACUSE, NEW YORK, ASSIGNOR TO PASS & SEYMOUR, INC.,
OF SOLVAY, NEW YORK, A CORPORATION OF NEW YORK.**

DESIGN FOR A SIGN-RECEPTACLE RING.

Application filed July 26, 1927. Serial No. 22,884. Term of patent 14 years.

To all whom it may concern:

Be it known that I, MARK N. RUSSELL, a citizen of the United States, and resident of Syracuse, county of Onondaga, State of New York, have invented a new, original, and ornamental Design for a Sign-Receptacle Ring, of which the following is a specification, reference being had to the accompanying drawing, forming a part thereof, and in which:

Figure 1 shows a portion of a ceiling

fixture in vertical section with a receptacle provided with a ring according to the present invention;

Figure 2 is a front elevation of a ring;
Figure 3 is a side elevation thereof; and
Figure 4 is a vertical central section.

I claim as my invention:

The ornamental design for a sign receptacle ring as shown.

MARK N. RUSSELL.
